H. V. WILLMAN,
SOCKET CARRIER FOR ELECTRIC FIXTURES,
APPLICATION FILED MAY 11, 1918.

1,309,051.

Patented July 8, 1919.

UNITED STATES PATENT OFFICE.

HERMAN V. WILLMAN, OF CHICAGO, ILLINOIS.

SOCKET-CARRIER FOR ELECTRIC FIXTURES.

1,309,051.

Specification of Letters Patent.

Patented July 8, 1919.

Application filed May 11, 1918. Serial No. 233,884.

To all whom it may concern:

Be it known that I, HERMAN V. WILLMAN, a citizen of the United States, residing at Chicago, Illinois, have invented certain new and useful Improvements in Socket-Carriers for Electric Fixtures; and I do hereby declare the following to be a full, clear, and exact description of the invention, such as will enable others skilled in the art to which

10 it appertains to make and use the same.

My invention relates to means for supporting the sockets of lighting fixtures, its general objects being to provide a socket-support which can readily be adjusted in 15 position with respect to a fixture, and which also can readily be removed entirely from the fixture when desired. More particularly, my invention aims to provide simple and effective means for shifting the position of a 20 lamp-socket with respect to other parts of a lighting fixture, so that the same light-distributing portion of the fixture may be used effectively with different sizes of lamps, or so that the same holder may be used effectively with different sizes or types of light-distributing members, and preferably to 25 provide adjusting means for this purpose which may be speedily manipulated without the use of tools and without dismantling 30 the fixture. Furthermore, my invention aims to provide a socket-support which may readily be shifted in position by manipulating parts accessible from the outside of the fixture, which will readily indicate the relative 35 position of the socket on the exterior of the fixture, which will not interfere with the speedy wiring of the socket, and which will rigidly hold the socket in any one of a number of predetermined positions. Still 40 other objects will be apparent from the following specifications and from the accompanying drawings, in which drawings—

Figure 1 is a fragmentary elevation of a lighting fixture, with parts of the casing and 45 of the reflector or globe cut away.

Fig. 2 is a fragmentary side elevation of the casing of the fixture of a portion of the socket-support of my invention.

Fig. 3 is an enlarged fragmentary elevation 50 of the socket-carrier of my invention as it would appear when removed from the case of the fixture.

Fig. 4 is a horizontal section taken through the casing of a fixture and immediately above a holder showing another embodiment of my invention.

In the embodiment of the drawings, my invention is shown as used in connection with a lighting fixture having a substantially cylindrical chimney 1 surmounted and supported by a cap 2 and substantially continued at its lower end by a spinning 3 which forms the holder for a light distributing member 4. The light-distributing member 4 in this instance is secured to the holder 3 by 60 screws 5 and may be any desirable form of reflector, refractor or globe. The cylindrical portion 1 of the casing is equipped on diametrically opposite sides with longitudinal slots 6, which slots have a plurality of 65 enlargements successively spaced from one another by about the same distances as the increase in the effective length of lamps of successively larger sizes; that is to say, the distances between the enlargements and the 70 slots 6 correspond to the difference in distance between the base end of a minimum size lamp and the center of the light-giving portion of the lamp and the corresponding distances on lamps of higher candle power. 75 Thus, Fig. 2 shows the slot arrangement as provided for enabling the socket and socket-carrier coöperating therewith to hold either a 100, or a 200, or a 300 candle power lamp in effective relation to the light-distributing 80 portion of the fixture. To cooperate with the slots thus described, I employ a socket-support having resilient portions continually pressed toward the slotted sides of the casing and carrying elements adapted 85 respectively to be interlocked with a pair of oppositely disposed enlargements in two slots. For example, Figs. 1, 2 and 3 show a socket carrier comprising a fork of resilient metal having arms 7 doubled back upon 90 themselves and carrying at its center a threaded bushing 8 adapted to be screwed into the bushing of the socket casing. The arms 7 are so spaced from each other that their resiliency will tend to spread the free 95 ends of these arms for a greater distance than the diameter of the casing 1, thereby normally pressing the tips of these arms against oppositely directed portions of the interior of the casing. Mounted on each of 100 the arms near its free end is an interlocking element having close to the arm a base portion of a size wider than the main portion of one of the slots 6, and adapted to enter one of the enlargements in the said slot. This 105 interlocking element also has a tip portion 9, desirably in the form of a knob, which tip

portion is spaced from the base portion 10 by a contracted neck 11 narrower than the width of the main portion of the slot 6. Thus, this interlocking element may consist 5 of a metal turning shaped as in Fig. 3 and threaded into a perforation in the arm 7, thereby also permitting this metal turning to be unscrewed and detached from the fork when desired, by manipulating the same 10 from outside the casing.

In operation, the resiliency and the shape of the arm portions of the fork normally hold the bases 10 of the two interlocking members seated in oppositely disposed enlargements in the two slots. For example, 15 the full lines of Fig. 1 show these interlocking elements as engaged with the metal enlargements of the slots, or with those corresponding to a proper supporting of the 20 socket for use with a 200 candle power lamp. Upon pressing the two knobs 9 toward each other sufficiently to bring the contracted 25 necks 11 opposite the walls of the slots, the entire socket-carrier can be slid in either direction, thus permitting it to be interlocked with the upper pairs of slot enlargements (or those suitable for use with a 300 candle 30 power lamp), or with the lowest pair of slot enlargements which correspond to the 100 candle power side of lamp. By exposing the knobs 9 so that they may be manipulated from the exterior of the fixture casing, I enable such needed adjustments to be made 35 instantly and without the use of tools. Moreover, this same exposing of the knobs enables the observer to note the position of the socket carrier instantly and without dismantling any part of the fixture or even detaching the reflector or globe. At the same 40 time, by suitably shaping the doubled-back portions of the resilient arms, I cause these to bear against the inner surface of the casing, 1 for a considerable distance, thereby preventing any tilting of the socket-carrier 45 with respect to the axis of the fixture and also preventing any looseness of the parts associated in this way. However, while I have illustrated and described my invention as 50 employed in connection with a certain type of fixture and with lamps of three different sizes, I do not wish to be limited to these or other details of the construction and arrangement here disclosed, it being obvious 55 that the same might be modified in many ways without departing from the spirit of my invention. For example, Fig. 4 shows the socket-carrier of my invention as comprising a bushing 12 having a pair of resilient arms 13 secured to opposite sides of 60 this bushing, so that these arms extend in substantially the same general plane transversely of the casing with the interlocking elements carried by them, instead of having the arms extend longitudinally of the casing. 65 In either case, it will be obvious that by

simply unscrewing the metal posts which normally interlock with enlargements of the slots, the socket-carrier will be left only frictionally engaged with the bore of the casing, so that this carrier may then be manually withdrawn after removing the light-distributing member 4.

Likewise, it will be obvious that the number of enlargements in each slot may be increased as desired, and that the spacing may 75 be altered also, thereby adapting my invention not only for use with lamps of different sizes but also with different types or sizes of reflectors or other light-distributors.

I claim as my invention:

1. A lighting fixture for affording a substantially predetermined light distribution from lamps of varying effective lengths, comprising a casing equipped on one side with a slot having a plurality of seat formations spaced longitudinally of the casing by distances corresponding to the successive differences in length of the several sizes of lamps; a reflector fast with respect to the casing and shaped for affording the desired 90 light distribution; and a socket-carrier housed by the casing and movable longitudinally of the latter; the said carrier including locking means projecting through the said slot and normally engaging one of the 95 said seat formations, and a resilient element carrying the locking means and normally holding the latter in its said engaging position; the projecting of the locking means permitting the latter to be manipulated from 100 the exterior of the casing to disengage the locking means from a seat formation and to move the said carrier from one to another of the seat formations so as to adjust the position of the carrier to any one of the 105 predetermined positions visibly defined by the location of the said seat formations as corresponding respectively to the several sizes of lamps.

2. In a lighting fixture, a casing equipped with a plurality of seat formations spaced longitudinally of the casing, and a socket-carrier housed by the casing and including a supporting element adapted interchangeably to engage the said seat formations in the bore of the casing, and having an extended longitudinal portion to engage the side of the casing to prevent lateral swinging of the carrier with respect to the casing, and resilient means for simultaneously forcing both the said element and the said other portion of the carrier into their aforesaid positions.

3. In a lighting fixture, a casing equipped on one side with a slot having a plurality of 125 seat formations spaced longitudinally of the casing; and a socket-carrier housed by the casing; and slidably longitudinally of the latter; the said carrier including a locking element projecting through the said slot 130

- and normally engaging one of the said seat formations, and a resilient element carrying the locking element and normally holding the latter in its said engaging position, the projecting of the locking element permitting the latter to be manipulated from the exterior of the casing for moving the latter element from one to the other of the said seat formations.
- 5 4. In a lighting fixture, a casing equipped on each of a plurality of sides with slots each including a series of seat formations spaced longitudinally of the casing, and a socket-carrier disposed within the casing and including a plurality of resilient arms each normally pressed by its own resiliency against the bore of the casing and each having an element disposed in one of the said seat formations, the last named elements being manually accessible from the outside of the casing for moving the socket-carrier from one to another of the positions defined by the said seat formations.
- 10 5. In a lighting fixture, a casing equipped on two sides with a plurality of seat formations spaced longitudinally of the casing, and a socket-carrier including a pair of resilient arms each bent back upon itself and presenting an end portion normally forced by the resiliency of the arm into engagement with the bore of the casing for a considerable portion of its length, the socket-carrier also including a locking element carried by the end of each resilient arm and normally engaging one of the said seat formations.
- 15 6. In a lighting fixture, a casing equipped on opposite sides with substantially longitudinal slots each having enlargements
- therein spaced longitudinally of the casing, 40 and a socket-carrier disposed within the casing and including a pair of posts respectively projecting into slot enlargements at opposite sides of the casing and resilient arms carrying the said posts and normally holding the latter seated in the said enlargements.
- 5 7. In a lighting fixture, a casing equipped on opposite sides with substantially longitudinal slots each having enlargements 50 therein spaced longitudinally of the casing, and a socket-carrier disposed within the casing and including a pair of posts respectively projecting into slot enlargements at opposite sides of the casing and resilient 55 arms carrying the said posts and normally holding the latter seated in the said enlargements, each of the said posts having a relatively contracted portion normally disposed outside the casing and of a diameter less 60 than the width of the main portion of the adjacent slot.
8. In a lighting fixture, a casing equipped on its opposite sides with a plurality of seat formations spaced longitudinally of the casing, and a socket-carrier including a single strip of resilient metal bent into a U shape and having the shank of each U bent back upon itself, and also including a pair of locking elements mounted respectively on 70 the doubled back portions of the said strip and respectively engaging seat formations on opposite sides of the casing.

Signed at Chicago, May 6th, 1918.
HERMAN V. WILLMAN.
